J. WIMMER

TABULATOR STOP OF CALCULATING MACHINES AND TYPEWRITING MACHINES

Filed April 14, 1922

Fig:1.

UNITED STATES PATENT OFFICE.

JOSEF WIMMER, OF SCHONAU, NEAR CHEMNITZ, GERMANY.

TABULATOR STOP OF CALCULATING MACHINES AND TYPEWRITING MACHINES.

Application filed April 14, 1922. Serial No. 552,509.

To all whom it may concern:

Be it known that I, JOSEF WIMMER, a citizen of the German Realm, residing at No. 3 Tuppaustrasse, Schonau, near Chemnitz, Germany, have invented certain new and useful Improvements in the Tabulator Stops of Calculating Machines and Type-writing Machines, of which the following is a specification.

- 10 In calculating machines and typewriting machines with a laterally movable paper carriage, the tabulator stops which serve for stopping the said paper carriage at determined distances corresponding to the columns of a sheet to be typed, are adjustably movable along the tabulator rack for the purpose of being set at distances from one another corresponding to the widths of the columns. The pitch of the teeth of this 15 tabulator rack is exactly the same as that of the type spacing mechanism of the machine that is, it is exactly equal to the distance between one type and the next in a calculating machine, or to the width of the types 20 in a typewriting machine.

It is however not always possible to place a sheet in such a position that the lines separating the columns will coincide exactly with the pitch of the teeth of the tabulator 25 rack. On the contrary in typing, the typed matter frequently encroaches upon or over the column lines, with the result that the typed sheet has a very bad general appearance. Moreover it has been left to the skill 30 of the typist to avoid that drawback, thus entailing a considerable loss of time.

The present invention has now for its object to obviate that drawback by providing an improved tabulator stop which will 35 allow of effecting a special adjustment or fine adjustment of the tabulator stop, in addition to the ordinary adjustment given by the teeth of the tabulator rack. This result is achieved by constructing the improved 40 tabulator stop in two parts which are capable of adjustment relatively to each other within the width of a letter or the space between the types. Of the said two parts, one part engages the teeth of the tabulator rack, and 45 the other part, which carries the tabulator stop proper, is caused by the adjusting operation to move towards this "fixed" part. By this means the improved tabulator stop 50 can be set exactly to the column line.

55 A constructional form of the invention designed more particularly for a calculating

machine is illustrated in the accompanying drawings in which:—

Fig. 1 is a rear elevation of the paper carriage.

Fig. 2 is a longitudinal section of the improved tabulator stop, drawn to a larger scale.

Fig. 3 is a side elevation, and

Fig. 4 is a plan of the column-setter.

The supporting frame 2, furnished with ball-bearing race and scale 1, is fixed on the rear frame of the calculating machine. The slide 5 of the paper carriage which is furnished with end plates 3, 4, is adapted to slide in the supporting frame 2. The lower ends of these end plates have recesses in which the tabulator rack 9 is mounted. This rack has two longitudinal grooves 6, 7 for guidance extending along its entire 70 length, and also transverse grooves 8 for adjustment; it is fixed in place by means of round knurled screwed nuts 9^a.

This tabulator rack may have any desired 75 number of tabulator stops 10 mounted on it. Each of these stops is provided with a cylindrical part 11 which is slidable along the tabulator rack and is formed with an annular groove 12 and two mutually facing recesses 13. In the bore of this part 11 there 80 is provided a feather-key 15 which is fixed by means of rivets 14 and is slidable in the groove 7 in the tabulator rack.

At the side of the part 11 and on the tabulator rack, there is mounted an adjusting member 16 having two externally screw-threaded jaws 17, 17 which engage in respective recesses 13 in the cylindrical part 11. These two jaws are connected operatively 85 together by a nut 26 which is mounted on the cylindrical part 11 and engages by means of its own internal screwthread with the external screwthreads of the jaws.

Three screws 27 in the nut 26 engages 90 by means of their plain ends 28 in the groove 12 of the cylindrical part 11, and thereby prevent lateral movement of the nut 26 relatively to the said part 11.

A feather-key 24 adapted to slide under the tabulator stop 10, is fixed by means of a rivet 23 in the bore of the adjusting member 16. This feather-key is capable of being slidden along in the groove 6 in the tabulator rack 9. A screw 25 fixed to the feather-key 24 limits the relative motion between 105 the parts 11 and 16 which is equivalent to the pitch of one tooth.

The adjusting member 16 has further a recess 18 in which is mounted a catch 21, 22 which is capable of rocking on the rivet 19, and partly encircles the tabulator rack. The 5 limb 22 of this catch projects of the recess 18 to a sufficient extent to form a thumb-piece for the operator. A spring 20 situated in a bored hole, acts upon this limb 22 in such a manner that the limb 21 of the 10 catch is normally always in engagement in one or other of the adjusting grooves 8 in the tabulator rack.

The paper carriage can be released by 15 operating the releasing lever 30 which is pivoted on a screw 29 carried by the end plate 4. The lower arm 31 of this releasing lever engages by means of a pin 32 in a recess in the arm 33 of a bell-crank lever fixed on the tabulator rack 9. A spring 35 which 20 is fitted between one arm of the bell-crank lever 33 and a lug-shaped extension of the releasing lever 30, acts to move the latter as well as the tabulator rack back into the normal position after release.

25 At the centre of the supporting frame there is fixed a bent plate 39 for holding the paper carriage. This plate has a recess 36 and also two oppositely inclined ramps 37, 38 arranged at an angle to each other. 30 A pawl 41 mounted on this plate and capable of rocking on a screw 40 serves for stopping each tabulator stop as it comes up against it. The movement of this pawl 41 is limited by stud screws 42, 43 fixed to 35 the plate 39.

The operation of the subject matter of the invention is as follows:—

When a printed sheet divided into columns is placed in the machine and is to be 40 filled with numbers, the operator moves the paper carriage so as to bring the first division line (counting from the operator's side of the machine) up to the first type bar on the right, and the operator then compares 45 the number of numerals to be typed with the number of type bars that are required. Then according to the resulting distance the operator moves the paper carriage into the position where this number can be typed 50 in the desired place. The operator then presses with his or her thumb upon the limb 22 of the catch of the nearest tabulator stop, whereby the limb 21 of the catch is tilted out of the adjusting grooves. The stop which has 55 been thus released, is pushed along until it falls into the notch 36 provided in the plate 39. When this has been done, the operator removes his or her thumb, and the limb 21 then snaps into the corresponding adjusting 60 groove in the tabulator rack. The dividing grooves provided in the tabulator rack correspond exactly with the spacing (that is, the distance between one type and the next) of the calculating machine.

65 If however, the setting effected by means

of the stop does not correspond with the column line, so that, for instance, the numeral to be typed, would come too far from one column-line, or even over the other column line, the operator turns the round nut 26 70 either to the right or to the left, whereby the adjusting part 16 which is fixed on the tabulator rack 9 causes by means of its screw-threaded jaws 17, the nut 26 to shift the stop proper 10, 11, and through the latter, 75 the paper carriage, so that the column line is brought into exact coincidence with the type spacing.

For the purpose of setting the other tabulator stops, the releasing lever 30 is again 80 thrown over so as to release the paper carriage, and the tabulator rack 9 is turned by means of the parts 31, 32 and 33 so that the stop 10 that was engaged in the notch 36, swings out of same. The operator then 85 shifts the paper carriage while letting go slightly the releasing lever, and the tabulator rack 9 together with the tabulator stops on it, is turned back again into the initial position by the spring 35 arranged between 90 the bell-crank lever and the releasing lever.

On the further shifting of the paper carriage to the left or to the right as far as the next column, the next following tabulator stop runs up on to the ramp 36 or 37 formed 95 on the plate 39, and strikes, while turning at the same time, against the pawl 41 (which is mounted on the said plate, and projects slightly beyond the ramps) until the said pawl comes to bear against one of the stud screws 42 or 43, whereby the stop 10 is compelled by the action of the spring 35 upon the tabulator rack to snap into the notch 36. The other settings are effected in the hereinbefore described way. 100

105 What I claim is:—

1. In a tabulating device for calculating machines and typewriters, the combination with a tabulator rack of a tabulator stop comprising a member engaging with the tabulator rack, a stop member on the tabulator rack capable of sliding thereon relatively to the said rack engaging member for adjusting purposes, the said stop member being intended to engage a carriage stop fixed to the frame of the machine, and means for adjusting the said stop member and retaining it in its adjusted position. 110

2. In a tabulating device for calculating machines and typewriting machines having a paper carriage, the combination with the tabulator rack, of a tabulator stop comprising a member engaging with the tabulator rack, a stop member adapted to engage in a notch in a part fixed to the frame of the machine, and to be shifted relatively to said rack engaging member, a releasable spring catch on said rack engaging member, engaging the tabulator rack, externally screwthreaded jaws, provided on the said 115 120 125 130

rack engaging member, said jaws engaging said stop member, a nut meshing by means of its internal screwthread with said externally screwthreaded jaws, an annular groove 5 in said stop member, and a pin on said nut, engaging in said annular groove, whereby when said nut is rotated said stop member is shifted relatively to said rack engaging member that is held fast by the tabulator 10 rack.

3. In a tabulating device for calculating machines and typewriting machines having a paper carriage, the combination with the tabulator rack, of a tabulator stop comprising 15 a member engaging with the tabulator rack, a stop member adapted to engage in a notch in a part fixed to the frame of the machine, and to be shifted relatively to said rack engaging member, a releasable spring 20 catch on said rack engaging member, engaging the tabulator rack, externally

screwthreaded jaws, provided on the said rack engaging member, said jaws engaging said stop member, a nut meshing by means of its internal screwthread with said externally screwthreaded jaws, an annular groove 25 in said stop member, and a pin on said nut, engaging in said annular groove, a feather-key fixed to said rack engaging member, for guiding the latter on the tabulator rack, said feather-key passing through the stop member, and a screw carried by said feather-key externally of said stop member, for limiting the shifting movement of said stop member 30 relatively to said rack engaging member. 35

In testimony whereof I have signed my name to this specification.

JOSEF WIMMER.
